UNITED STATES PATENT OFFICE.

WILLIAM M. BLECKER, OF CANTON, OHIO, ASSIGNOR TO EDWARD A. LANGENBACH,
OF CANTON, OHIO.

CONTINUOUS-SHEET-ROLLING METHOD.

Original application filed December 7, 1925, Serial No. 73,597. Divided and this application filed June 30, 1926. Serial No. 119,675.

This invention relates to the continuous rolling of sheet bars, light plates or slabs into sheets of desired gauge, and the object of the improvement is to provide a method 5 in which sheet bars, light plates or slabs are heated and passed continuously through a series of roughing mills, being matched or piled once, twice or more depending upon the gauge of sheets to be rolled, the pieces 10 being then reheated and automatically doubled, if sheets under 22 gauge are desired, and then continuously passed through finishing rolls through side and end shearing apparatus, then through a continuous 15 annealing furnace and finally through sheet levelling and opening mechanism and onto a cooling table; each succeeding stand of rolls throughout the train being operated at a higher speed than the preceding rolls in 20 order to accommodate the increasing length of the bars or sheets as they are passed through each stand.

An embodiment of an apparatus for carrying out the invention is illustrated in the 25 accompanying drawings, in which

Figure 1 is a plan sectional view of the forward end of the train of apparatus showing the bar heating furnaces, wire scrubbing rolls, the first series of four stands of 30 roughing mills, the first matching table and the first stand of the second series of roughing mills;

Fig. 2, a longitudinal sectional view of the same;

Fig. 3, a plan sectional view showing the continuous reheating furnace, used for rolling sheets lighter than 22 gauge, the remaining three stands of roughing mills in the second series, the second matching table and 40 the first stand of finishing rolls;

Fig. 4, a longitudinal sectional view of the same;

Fig. 5, a plan sectional view showing a continuous sheet reheating furnace located 45 beyond the first stand of finishing rolls, the second and third stands of finishing rolls, a continuous sheet reheating furnace used for lighter than 22 gauge sheets and the fourth stand of finishing rolls;

Fig. 6, a longitudinal sectional view of the same;

Fig. 7, shows the last two stands of finishing rolls and the side trimming apparatus used for heavier than 22 gauge sheets;

Fig. 7^a is a view in cross section taken on 55 line 7^a—7^a of Fig. 7.

Fig. 8, a vertical longitudinal section of the same;

Fig. 9 shows the sheet end trimming apparatus, the continuous open annealing furnace and the sheet leveler used for sheets 60 heavier than 22 gauge;

Fig. 10, a vertical longitudinal section of the same;

Fig. 11, the pack loosening and opening 65 apparatus and cooling table for sheets heavier than 22 gauge;

Fig. 12, a vertical longitudinal section of the same;

Fig. 13, a plan sectional view of the doubling apparatus, continuous open sheet furnace, the first stand of finishing mills and 70 the first stand of edge straightening rolls, for rolling sheets lighter than 22 gauge;

Fig. 14, a vertical longitudinal section of 75 the same;

Fig. 15, a plan sectional view of the remaining alternate finishing mills and edge straightening rolls which succeed those 80 shown in Fig. 14;

Fig. 16, a vertical longitudinal section of the same;

Fig. 17, a plan sectional view of the side and end shearing apparatus and pack loosening and opening mechanism for lighter than 85 22 gauge sheets;

Fig. 18, a vertical longitudinal section of the same;

Fig. 19, a plan view of the cooling table located beyond the pack opening mechanism, 90 and

Fig. 20, a vertical longitudinal section of the same.

Similar numerals of reference indicate corresponding parts throughout the drawings.

One or more continuous bar heating furnaces 1 are provided for heating sheet bars, light plates or slabs which are placed on edge in the furnace as indicated at 2 and continuously moved therethrough as by a pusher 3, the bars being pushed from the furnace one at a time, as they are properly heated, and dropped flatwise upon a roller table 4 upon which they are carried between a pair of wire scrubbing rolls 5 which remove the loose oxide from the bars.

The bar is then passed successively

through four stands of roughing mills indicated at 6, 7, 8 and 9 each of which is operated at a higher speed than the next preceding stand. The piece is entered into the bite of the rolls of each stand by an automatic straightening and conveying device which comprises a pair of endless chains 10 mounted upon sprockets or rollers 11 driven preferably by an electric motor which drives the adjacent stand of rolls.

Each pair of these chains is connected by a bar or rod 12 arranged to be engaged by the piece which automatically throws in a clutch to operate the sprockets 11 from the motor. The chains are revolved around the sprockets, the piece being conveyed upon the chains into the bite of the rolls, until the bar 12 is again in its original position when the clutch is automatically thrown out as by operation of a limit switch.

The bar is reduced in thickness and increased in length as it passes through each succeeding stand of roughing mills and for this reason each succeeding stand is spaced a greater distance from the preceding stand and is operated at a higher speed.

In roughing bars for sheets lighter than 22 gauge the bars as they pass through the stand 9 of roughing rolls are deposited upon a matching table 13. This matching table is formed by inclining one section of the table toward the center as shown at 14. A pair of chains 15 are located around sprockets 16 carried by this inclined portion of the table, said chains being connected by a bar 17.

This matching table is only used for rolling sheets lighter than 22 gauge. Straightening fingers of usual construction are preferably provided upon the matching table for properly straightening the pile. When two sheets have been piled or matched upon the inclined portion of the table, as shown in Fig. 2, the sprockets 16 are manually set in operation, the bar 17 engaging the rear edge of the pile and pushing the same into the bite of the rolls in the stand 18 of roughing mills. Where heavier than 22 gauge sheets are to be rolled the sheets are not matched or piled upon this matching table but are carried singly into the stand 18.

A small continuous reheating furnace 18^a is located between the stands 18 and 19 for use only where lighter than 22 gauge sheets are being rolled. The piles are passed through the stand 19 to a roller table 20, thence through a stand 21, upon a roller table 22 and through the final stand 23, or roughing mills. Each of the stands 18, 19, 21 and 23 is operated at a higher speed than the next preceding stand.

As the piles are passed through the last stand 23 of roughing mills they are deposited upon another matching table 24.

similar to the table 14, where they may be matched one or more times, depending upon the gauge of sheets to be rolled.

When the proper number of piles of sheets has been deposited upon the matching table 24, the table is operated to move the pile into the bite of the rolls of the first stand 25, of finishing mills, after which the pile is passed through a small continuous open reheating furnace 26 and then successively 75 through the stands 27 and 28 of finishing mills and, if rolling sheets heavier than 22 gauge, through a continuous open sheet furnace 29.

The usual roller tables are located between 80 the stands and suitable tension guides 29^a are provided for properly placing the pile in each stand of rolls. In rolling sheets of 22 gauge or heavier the pile is then passed through three successive stands of finishing 85 rolls indicated at 30, 31 and 32, suitable roller tables and tension guides being provided between the same, and as the pile passes through the last stand 32 of finishing rolls it is received upon an endless conveyer 90 table 33 provided with magnets which are automatically energized as the pile passes onto the table, thus holding the pile rigid as it is moved, by the table, through the rotary shear blades 34, which trim the side 95 edges of the sheets to the desired width, as shown at 35.

The magnets upon the conveyer 33 are automatically deenergized as the trimming of the side edges of the pile is completed, 100 releasing the pile and carrying it onto the roller table 36 by which the pile is conveyed to end trimming shears 37 which operate in a manner illustrated in the prior art, to trim the front and rear ends of the pile to the 105 desired length, the trimmed pile being then conveyed by a roller table 38 through a continuous open annealing furnace 39 and then successively through a roller leveler 40 and a loosening and opening apparatus 41 which 110 may comprise staggered pairs of rolls 42 which alternately bend the pile in opposite directions to loosen the sheets.

This opening device may include a knife 43 located within a guide 44, the pile being 115 drawn through this guide and over the knife by the rolls 45 which separate the sheets of the pile and pass the same onto a roller table 46 by which the sheets are conveyed to a cooling table 47 of any usual and well known 120 design.

In rolling sheets lighter than 22 gauge, the apparatus is slightly different, from that above described, after the pile is passed through the reheating furnace 29. The pile 125 of light sheets after emerging from the furnace 29 is placed upon an automatic doubler, a pusher 48 or the like being used for this purpose. This doubler comprises a table 50, one-half of which, as indicated at 51, is 130

hinged at the center as at 52, a magnet 53 being carried by each half of the table, close to the hinge joint.

As the pile is placed upon this table it engages a stop which automatically energizes the magnets 53, holding the pile rigid upon the table at points close to the hinge joint. At the same time a clutch, connecting a suitable motor with the rocker shaft 54, is thrown in, rotating this rocker shaft in the direction of the arrow shown in Fig. 14. This rocker shaft carries a rocker arm 55 connected, by a link 56, with the hinged section 51 of the doubler table throwing this hinged section into the position shown in dotted lines in Fig. 14 and since the pile is held by the magnets, only at points close to the hinge, the free ends of the sheets in the pile are permitted to open as the pile is doubled, forming a pack as illustrated at 57 in Fig. 14.

When the hinged section of the doubler table reaches the position shown in dotted lines in Fig. 14 it engages a stop which changes the clutch connection returning the hinged section to the normal position and at the same time the magnets are automatically deenergized and the pusher 48 operated to move the pack from the doubler and upon a roller table 58 by which it is conveyed through a continuous open sheet furnace 59 and thence to the first stand 60 of a second series of finishing rolls. The upper roll 61 of this stand is preferably of larger diameter than the lower roll in order to flatten the forward end of the heated pack as it is well known that there is a tendency for this forward end of the pack to bend or curve upward as it emerges from the furnace. The pack is then conveyed through a series of alternate edge straightening rolls 62 and finishing rolls 63, each edge straightening roll being considerably smaller in diameter than the finishing rolls and being smaller at its center than at its ends so that the edges of the pack will be rolled down without striking the center of the pack and taking out the form of the preceding rolls, thus placing the pack in the next stand of finishing rolls as near to its original condition as possible and without breaking the pack open.

The pack is then conveyed through a side shearing apparatus 34^a and end shearing apparatus 37^a similar to the shearing apparatus 55 34 and 37 above described and then through a loosening and opening apparatus 41^a—45^a similar to the apparatus 41—45 above described and thence to a cooling table 47^a of any usual construction.

This application is a division of my co-pending application for improvements in continuous sheet rolling apparatus and method, Serial Number 73,597, filed December 7, 1925.

I claim:—

1. The method of continuous rolling of sheets from bars and the like which consists in passing heated bars successively through a series of roughing mills, matching and re-heating the reduced bars, passing them through a second series of roughing mills, again matching and reheating them, and passing the matched piles through a series of finishing mills, all in a single continuous pass.

2. The method of continuous rolling of sheets from bars and the like which consists in passing heated bars successively through a series of roughing mills, matching and re-heating the reduced bars, passing them through a second series of roughing mills, again matching and reheating them, passing the matched piles through a series of finishing mills, doubling and reheating the piles, and passing the double packs through a second series of finishing mills, all in a single continuous pass.

3. The method of continuous rolling of sheets from bars and the like which consists in passing heated bars successively through a series of roughing mills, matching and re-heating the reduced bars, passing them through a second series of roughing mills, again matching and reheating them, passing the matched piles through a series of finishing mills, doubling the piles and passing the doubled packs through a second series of finishing mills and rolling them to sheets of desired gauge all in a single continuous pass.

In testimony that I claim the above, I have hereunto subscribed my name.

WILLIAM M. BLECKER.
